UNITED STATES PATENT OFFICE.

JOHN SCHURS, OF LOS ANGELES, CALIFORNIA.

OIL-BURNER.

1,075,947.

Specification of Letters Patent.

Patented Oct. 14, 1913.

Application filed October 20, 1910. Serial No. 588,027.

To all whom it may concern:

Be it known that I, JOHN SCHURS, a citizen of the United States, residing at Los Angeles, in the county of Los Angeles and 5 State of California, have invented certain new and useful Improvements in Oil-Burners, of which the following is a specification.

This invention relates to improvements in hydrocarbon burners and particularly to 10 such as are adapted for use in connection with a steam or other jet, for breaking up and atomizing the oil, so as to produce the desired combustion.

It is an object of the invention among 15 other things, to provide a burner by which a comparatively small, hot fire may be secured close to the burner, so that the burner is well adapted for use in brick or other kilns where a number of small fires are employed.

It is also an object of the invention to provide a burner in which steam and oil may be commingled within the body portion of 25 the burner, after which these products are spread and then brought together again, at the discharge end of the burner, so that a flame is secured quite close to the burner.

It is a further object of the invention to 30 provide the burner with means in the form of a perforated hood for preventing the suction of air due to the blast from the burner, from carrying the flame too far therefrom.

With these and other objects in view, the 35 invention consists, in certain novel constructions, combinations and arrangements of parts, as will be hereinafter fully described and claimed.

In the accompanying drawing:—Figure 1, is a longitudinal central sectional view 40 through the improved burner. Fig. 2, is a detail perspective view of the discharge end of the burner, showing the spreader and with the hood of the burner removed. Fig. 3, is an end view of the burner, looking at the 45 discharge end thereof, a portion of the hood on said end being broken away to show the interior construction. Fig. 4, is an end view of the spreader and adjacent parts showing a modified form thereof, the hood being removed. Fig. 5, is a similar view with the 50 hood in place, parts thereof being broken away, the said hood being shown with an elongated discharge slot instead of a circular outlet. Fig. 6, is a sectional view 55 through a portion of a kiln the burner being shown in position and in side elevation.

While the burner forming the subject matter of the present invention is capable of use in various places, it is particularly well adapted for the burning of crude oil in brick 60 or other kilns.

The burner is constructed with an inner atomizing section, an elongated mixing chamber and an end spreader operating in conjunction with a concentrating hood. The 65 body portion 1 of the burner is formed, preferably by casting, with a central steam chamber 2, communicating with a steam inlet pipe 3 and an outer oil chamber 4, surrounding a portion of the steam chamber 70 and communicating with an oil supply pipe 5. One end of the steam chamber 2 is made open, but is normally closed by a removable screw plug 6, the construction permitting of an easy access to the interior of the 75 burner when it needs cleaning. The end of the chamber 2 opposite to the plug 6, is extended to form a steam jet or nozzle 7. The bore of said jet or nozzle is usually formed straight for a portion of its length as clearly 80 shown in Fig. 1, but is reduced in size at the discharge end of the jet or nozzle, as at 8. The discharge outlet 8 is also somewhat contracted toward its open end to secure the desired compression upon the steam as it 85 escapes into the mixing chamber. The oil chamber 4 is formed with an outlet portion as 9 around the jet or nozzle 7.

The mixing chamber 10 is formed in a hollow section 11, of the burner, which is 90 formed with an enlarged flaring end adapted to receive the outlet portion 9 of the oil chamber, upon which it is screwed as at 12. The interior contour of the enlarged end of 95 said section 11, is flared so as to almost conform to the exterior tapering end surface of the jet or nozzle 7. A slightly contracting annular passage 13 is thus secured around the tapering end of the jet or nozzle 7. The discharge end of the section 11, is provided 100 with a projecting spreader 14 which increases in diameter from its base outwardly to a point near its end, beyond which point the end of the spreader rapidly contracts so as to form a rounded end portion on the 105 spreader, as clearly shown in Figs. 1 and 2 of the drawing. Divergent passages 15 are formed in the section 11 around the base of the spreader 14 so that the atomized mixture may pass from the mixing chamber 10 110 outwardly around the said spreader. The end of burner section 11 adjacent to the

spreader is somewhat enlarged and provided with external screw threads as at 16 for receiving and holding in place the hood 17 of the burner. The said hood 17 is 5 formed with a nozzle 25, which is adapted to fit over the rounded end of the spreader 14, leaving a slightly converging passage between the two. A comparatively small discharge opening 18 is provided in the 10 nozzle 25, opposite the end of the spreader 14. An outwardly flaring flange 19 is formed upon the hood for preventing the suction of air around the discharge end of the burner from carrying the flame away 15 from the said burner. A series of apertures 20 formed in the said flange 19 extend around the base thereof or near where it springs from the hood 17. These holes or 20 apertures 20 admit sufficient air within the flange 19 to insure a thorough combustion of the comminuted oil, quite close to the discharge outlet 18. These holes 20 are also 25 found to be very effective in preventing any clogging within the flange 19, operating to maintain the face of the nozzle entirely clean around the discharge outlet and within the flange 19.

As shown in Figs. 4 and 5 it is sometimes 30 advantageous to form the spreader with opposite flattened sides as 21, and in this instance the nozzle is provided with an elongated slot as 22, preferably extending parallel with the flattened faces 21 of the spreader. This tends to form a broad horizontal flat flame, instead of a round concentrated flame as is the case with the round opening 18, heretofore described. The 35 burner of the types described, with either the round outlet or the slot outlet, is admirably adapted for use in connection with brick kilns, where a large number of small fires are required. The burner is usually mounted as shown in Fig. 6, at one of the 40 openings 23 of the kiln and extends inwardly toward the wall 24 of the flue formed in the kiln. The flame produced by this burner is not projected from the same far enough to drive the said flame with force against the wall 24, as is the case with 45 burners that are not formed so as to hold the fire in close proximity to the discharge end of the burner. With the burner of the present invention, also the flame remains sufficiently near the hood to keep the end of 50 the burner warm or moderately heated which insures a thorough combustion of the atomized oil after it has escaped from the opening 18.

The construction of the burner is important 60 in having an inner atomizer and a spreader, together with the hood which draws the mixed products together again so

that they are thoroughly commingled just before being ignited. The contracting converging discharge ends of the steam and oil nozzle cause the oil to be thoroughly atomized and mixed with the steam as it is drawn into and forced through the mixing chamber 10. The spreading of the atomized oil by the spreader 14, makes it possible to draw the atomized mixture together again around the end of the spreader so that the commingled hydrocarbon and steam are concentrated at the discharge outlet 18 and yet in such a manner that they will not be projected to any great distance from the hood. As above intimated the flange 19 cooperates with the nozzle and checks the influx of the external air so as to prevent the carrying of the flame away from the burner too far and fast. The openings 20 provide however for a proper feeding of sufficient air to the flame, for supporting thorough combustion and preventing any collections of oil or dirt or other clogging materials within the flange 19, or around the discharge outlet.

The construction of the burner is also such that its parts can be readily cast in manufacture and thus produced in an economical manner.

While I have described the invention as particularly well adapted for use in kilns, it will be understood that it may be employed with great facility in any other place where a close fire is desired all within the spirit and scope of the invention.

Having now described my invention what I claim and desire to secure by Letters Patent, is:

1. A burner made up of a steam and oil feeding jet portion, and having a fuel mixing chamber, a fixed spreader arranged at the outer end of said mixing chamber and formed with a rounded outer end and a removable cap having a discharge opening of less diameter than the diameter of said rounded end portion, whereby a flame is produced close to the burner.

2. A burner, comprising an oil atomizing portion, a mixing chamber portion, a spreader mounted at the discharge end of the mixing chamber portion having an outer rounded end, a removable cap mounted over the end of said spreader and having a discharge opening of less diameter than the said spreader, the said cap having a flange provided with apertures therein for controlling the admission of air to the flame.

In testimony whereof, I have hereunto set my hand, in presence of two witnesses.

JOHN SCHURS.
